UNITED STATES PATENT OFFICE.

ISAAC NEWTON YOUNT, OF DRINKWATER, SASKATCHEWAN, CANADA.

GRAIN STOOKER.

Application filed August 16, 1920. Serial No. 403,967.

To all whom it may concern:

Be it known that I, ISAAC NEWTON YOUNT, of the town of Drinkwater, in the Province of Saskatchewan, Canada, have invented certain new and useful Improvements in Grain Stookers, of which the following is the specification.

My invention relates to improvements in grain stookers and the object of the invention is to devise a simple and cheap form of stooker which can be readily attached to a binder frame so as to travel therewith and it consists essentially of the following arrangement and construction of parts as hereinafter more particularly explained.

Fig. 1 is a side elevation of my stooker and a portion of a binder indicating the relative position of the stooker thereto.

Fig. 2 is a plan view of my stooker showing its relative position to the binder deck of a binder.

Fig. 3 is a plan view with the sheaf receiver removed.

Fig. 4 is an end elevation of the stooker showing the normal position of the receiver in full lines, the intermediate position ready for the discharging of the shock by dotted lines and of the discharge position or position the receiver assumes when the stook is up-ended in dashed lines.

Fig. 5 is a plan view of the sheaf receiver showing it in the sheaf receiving position in full lines, and in the intermediate position as it is swung to the discharge position and as the compressor arm mechanism engages the cam 90 shown in dotted lines, and the position it assumes when passing the cam 90 during its return movement in dashed lines.

Fig. 6 is a side elevation of the sheaf receiver looking from the opposite side to that shown in Fig. 4.

Fig. 7 is a plan view of my sheaf receiver separate from the rest of the mechanism.

Figs. 8, 9 and 10 are detail plan views showing the compressor arm mechanism co-acting with the cam 90, Fig. 8 being in the position the mechanism assumes when engaging the cam, and Fig. 9 in the position the mechanism assumes when leaving the cam, and Fig. 10 in the position the mechanism assumes when returning past the cam.

Fig. 11 is a side elevation of the sheaf receiver shown in Fig. 7.

Fig. 12 is a detail view showing the engaging portion of the lever 86 in contact with the frame 14.

In the drawings like characters of reference indicate corresponding parts in the various figures.

Referring to Figure 1 a portion of a binder frame 1 is illustrated with the position of the main wheel thereof indicated by the reference numeral 2. The sprocket drive 3 and discharge deck 4 are of conventional form. Referring to Figures 1, 2 and 3 the main carriage 5 of the stooker which comprises a frame 6 secured at one end to the frame of the binder and supported at the opposite or outer end by a carrier wheel 7 mounted upon the shaft 8 journalled in suitable bearings carried by the frame 6. 9 is a supplemental structure formed by two bars 10 and 11 which are supported crosswise of the main frame 6 upon the longitudinal timbers 12 and 13 of such main frame. The bars 10 and 11 project laterally from the frame 6 so as to overhang the same and are positioned at the right side of the binder.

14 is a turnable frame which is mounted upon a vertical shaft 15 carried in the cross bar 16 of the main frame. The frame 14 is divided into two portions 17 and 18 which are hinged together at 19. (See Fig. 4.) The cross bar 16 of the portion 17 is secured to the shaft 15. 20 is a sheaf receiver support which it carried by the portion 17 of the frame 14 and extends upwardly therefrom. 21 is an arcuate track which is supported upon the main frame 5 and is substantially concentric to the centre of the shaft 15. The portion 18 of the frame 14 is provided intermediately of its length with a cross bar 22 between which and the end bar 23 of the frame is mounted a roller 24. The roller 24 bears upon the track 21 so as to support the end of the frame 14 which is remote from its centre of swing of such frame as will hereinafter be explained. 26 is a sheaf receiver which is open at both ends and tapered in form. The large end 27 is provided with a hinge 28 connecting the receiver to the outer end of the portion 18 of the frame 14. 29 is a series of tines which are secured to the rod 29 forming the hinge pin of the hinge 28. The tines 29 extend upward in front of the open broad end of the sheaf receiver so as to form a support for the butt ends of the sheaves as the receiver is up-ended.

30 is a wedge shaped projection which extends upward from the bottom of the receiver 26 and forms means whereby the butts of the sheaves are spread apart to form a broad

end for the shock so as to render the shock stable when up-ended. 31 is a compressor member which extends crosswise of the receiver in proximity to the small end thereof and is bowed upward.

The ends of the compressor member are provided with trunnion portions 32 and 33 turnably held in the side walls of the receiver 26. 34 is a crank arm which is secured to the trunnion 33. 36 is a spring finger which is carried by the sheaf receiver at its opposite end and to which is pivotally connected a rod 37 pivotally connected at its opposite end to the upper end of the crank arm 34. The crank arm 34 is held in its normal position by tension spring 36, connected at one end to the crank arm 34 and at the opposite end to the sheaf receiver 26. 38 and 39 are arms swingably mounted at their inner ends in brackets 40 and 41 carried by the longitudinal bar 12 of the main frame 6. 42 is a roller which is journaled between the free ends of the arms 38 and 39. The upper peripheral portion of the roller 42 is flush with the upper face of the track 21 so that as the roller 24 travels around upon the track 21 it passes on to the roller 42 and is temporarily supported thereby. The roller 42 is supported in the normal position by a turn roll 43 provided with crank arms 44 and 45. The rod 43 is operated by any suitable form of lever which is held in position by a co-acting rack quadrant and pawl (not shown), located in proximity to the seat of the driver of the binder. 47 is a bevel gear secured to the lower end of the shaft 15. 48 and 49 are opposing bevel gears freely mounted upon the shaft 8 and meshing with the opposite sides of the bevel gear 47. The bevel gears 48 and 49 are provided with ratchet clutch members 50 and 51 formed integral therewith. 52 and 53 are clutch members which are splined upon the shaft 8. The clutch members 52 and 53 are provided with annular grooves 54 and 55 with which the clutch operating forks 56 and 57 engage. The fork 56 is operated by a lever 59 which is pivotally mounted at 59^x upon the bar 11 carried by the main frame 5. The free end of the lever 59 is connected by a pull cord 60 or by any other suitable means to an operating lever located on the binder in proximity to the driver's seat. 61 is a curved lever which is also mounted at 59^x and provided with a pressure spring 161. The inner end of the lever 61 bears against the end of the rod 62 which is connected to the clutch arm 56 and which is provided with a spring 162 weaker than the spring 161. The opposite end of the lever 61 is provided with an upward projection 63 for a purpose which will herein-after appear.

64 is a lever which is pivoted at 64^x

upon a bracket 64° and which is connected at one end to the fork 57. 65 is a lever which is mounted upon the cross bar 11 one end of the lever being connected by a pull cord 66 to a suitable operating lever mounted upon the binder in proximity to the driver's seat. The opposite end of the lever 65 is provided with a roller 62^x. 63^x is a spring held rod having at one end a head 66^x having an inclined face with which the roller 62^x coacts. The opposite end of the rod 63^x is connected by a link 70^x to the lever 64. 65^x is a bar spring held in a bracket 65° against which the outer end of the lever 65 bears. The lever 65 is provided with an upward projection 67 held against the inner end of the bar 65^x. 68 is an elevating conveyor of any suitable type. It is preferably formed by endless chains 69 connected together by cross bars 70 carrying pronged teeth 71 for engaging the sheaves. 72 and 73 are standards extending upward from the side boards 74 of the conveyor. 75 and 75^x are bars through which the standards 72 and 73 freely extend. 77 is a bar carried by the bars 75 and 75^x. The lower end of the bar 77 is curved upward at 77^x and the upper end of the bar is curved downward at 77°. 78 are tension springs connecting the bars 75 and 75^x to the standards 72 and 73. Bars 77 may be arranged either at each side of the elevating conveyor or in the centre as shown or may be arranged at intervals across the conveyor so as to exert a pressure on the sheaves as they pass outward and hold them in engagement with the prongs 71 of the conveyor. The lower end of the elevating conveyor 68 is provided with a receiving board 79 which extends at its outer edge beneath the discharge deck 4 of the binder. As the sheaves are discharged from the binder 4 they are conveyed upward by the conveyor prongs 71 and are thrown successively into the sheaf receiver 26. When the required number of sheaves have been conveyed into the receiver the pull cord 60 is pulled so as to carry the clutch member 52 into engagement with the clutch member 50 and thereby drive the bevel gear 48 from revolving shaft 8 and thereby turn the bevel gear 47 and the shaft 15 on which such bevel gear is secured. As before recited the frame 14 is connected to the shaft 15 so as to turn therewith. The end of the frame 14 which is normally the forward end is thereby swung around through an arc of 180 degrees, into the position indicated by dotted lines in Fig. 3, the roller 24 travelling upon the track 21 so as to support the frame during this movement until it passes on to the roller 42. It will thus be seen that the butts of the sheaves which are normally directed forward are carried around so as to be 130

directed rearward. When the receiver is brought to this position the frame 14 engages the upward projecting portion 63 of the arm 61 thereby carrying the clutch member 52 out of engagement with the clutch member 50 and thereby stopping the turning of the frame 14.

As soon as this movement is complete the turn rod 43 is released by disengaging the pawl of the operating lever from the rack hereinbefore referred to allowing the arms 38 and 39 and roller 42 to drop and thereby allowing the portion 18 of the frame 14 to drop or hinge downward into the inclined position as indicated by dashed lines in Fig. 4.

As the frame portion 18 strikes the ground the sheaf receiver 26 is thrown upward on its hinges by the impact of the part 18 striking the ground so as to carry the receiver into the vertical position as indicated by dashed lines in Fig. 4. By this movement the butt end of the shock is thrown against the ground and is positioned on the tines 29. Simultaneously the spring finger 36 strikes the ground forcing the rod 37 longitudinally and the compression arm into the position indicated in Fig. 4 so as to clear the shock and allow it to pass outward from the receiver. As soon as the receiver is released of the weight of the shock it is carried backward to its normal position by means of the tension spring 80. The turn rod 43 is then turned by its operating lever hereinbefore referred to in the opposite direction to that previously described thereby raising the roller 42 and the frame portion 18 and receiver 26 to the horizontal position. When this is accomplished the pull cord 66 is pulled thereby carrying the clutch member 53 into engagement with the clutch member 51 and the intermeshing gears 49 and 47 driving the shaft 15 in the reverse direction so as to carry the receiver 26 back to its normal position.

In order to prevent the sheaves which are continually fed from the elevating conveyor 68 from falling as the sheaf receiver 26 is turned and during the deposition of the shock I have provided the following mechanism.

81 are standard bars extending outwardly in the inclined direction from the side boards of the elevating conveyor 69, and 82 is a rod which is journaled in the outer ends of the bars 81. 83 are a series of curved tines which are formed integral with the rod 82 and which form a receiving basket adapted to receive the sheaves thrown from the upper end of the conveyor. 84 is a crank arm secured to one end of the rod 82. 85 is a standard support which extends either from the frame of the elevating conveyor or may extend from the main frame of the

shocker. 86 is a lever pivoted to the support 85 and connected at its upper end by a link 87 to the arm 84. 88 is a projection extending from the lever 86 which is adapted to engage the frame 14. Normally 70 the projection 88 bears against the side of the frame 14 so as to hold the lever and the co-acting parts in the position indicated by full lines in Fig. 1.

When, however, the sheaf receiver is 75 swung in a horizontal plane to discharge the shock the projection 88 is released with the lever 86 and the tines 83 dropped by gravity into the position indicated by dotted lines in Fig. 1, and in close proximity to the 80 upper end of the conveyor 68, the tines 83 remaining in this position during the up-ending of the shock.

When the receiver 26 returns to its normal position the projection 88 is struck by 85 the frame 14 thereby swinging it back to its normal position and carrying the tines 83 from the position indicated by dotted lines back to the position indicated by full lines. As the tines are carried to this position the sheaves held thereby are discharged so as to drop into the receiver 26. The remaining number of sheaves required to form the shock are then fed directly from the conveyor 68 into the receiver and when the number is complete the up-ending operation of the sheaf receiver to discharge the shock is performed.

It will be understood that as the sheaf receiver discharges the stock and returns and is again recharged with sheaves, the compressor arm is held clear of the sheaves by the spring 36* and is not thrown into the compressing position until after the recharging operations. In order to accomplish this, I have provided the opposite end of the compressor arm with a crank arm 89 connected by a link 89* to an arm 90*. 90 is a cam member provided with a spring finger 91 suitably supported as by a standard A on the main frame. As the arm 90* is carried inward towards the elevating conveyor it springs past the finger 91. As the receiver moves in the opposite direction, the arm passes on the other side of the finger and engages the cam so as to force the spring held compressor arm into the compressing position against the sheaves.

From this description it will be seen that I have devised a very simple form of stooker which will quickly and easily up-end the shock leaving it in a firm and stable position upon the ground.

What I claim as my invention is:

1. In a stooker, the combination with a stooker carriage and means for connecting the carriage to a binder, of a sheaf receiver turnably mounted upon the carriage, means for turning the receiver in a horizontal plane to carry the butts from a forwardly

presented position to a rearwardly presented position, means for permitting the butt holding end of the receiver to swing downward to the ground upon reaching the aforesaid position, and connecting means between the receiver and the carriage adapted to allow of the up-ending of the receiver as it is brought into contact with the ground.

2. In a stoker, the combination with a stoker carriage and means for connecting the carriage to a binder, of a sheaf receiver turnably mounted upon the carriage, means for imparting a turning movement to the receiver in a horizontal plane, releasable means for permitting the butt holding end of the receiver to swing into contact with the ground after the turning operation and whereby the sheaf receiver is up-ended to discharge the shock.

3. In a stoker, the combination with a stoker carriage and means for connecting the carriage to a binder, of a frame turnably mounted upon the carriage in a horizontal plane in proximity to one end, a hinged extension to the turnable frame, means for turning the frame, means for releasably supporting the free end of the frame in its normal position, means for releasing such free end of the frame after its turning operation to bring it into contact with the ground and a sheaf receiver hingedly connected at its butt holding end to the free end of the frame.

4. In a stoker, the combination with a stoker carriage and means for connecting the carriage to a binder, of a frame divided into two portions hingedly connected together, means for turnably mounting one portion in a horizontal plane upon the stoker carriage, means for turning the frame, means for releasably supporting the free end of the other portion, releasable means adapted to release the free end of the frame after its turning movement, and a sheaf receiver hingedly connected to the free end of the frame.

5. In a stoker, the combination with a stoker carriage and means for connecting the carriage to a binder, of a frame divided into two portions hingedly connected together, means for turnably mounting one portion in a horizontal plane upon the stoker carriage, means for turning the carriage, means for releasably supporting the free end of the other portion, releasable means adapted to release the free end of the frame after its turning movement, a sheaf receiver hingedly connected to the free end of the frame, and resilient means for returning the sheaf receiver from its up-ended position after being relieved of the weight of the shock.

6. In a stoker, the combination with a stoker carriage and means for connecting the carriage to a binder, of a main shaft

carried by the carriage, a carrier wheel mounted upon the outer end of the main shaft, a frame divided into two portions hingedly connected together, a shaft mounted upon the carriage and to which one of the frame portions is secured, a bevel gear secured to the lower end of the shaft, bevel gears freely mounted upon the main shaft and adapted to engage with the aforesaid gear at diametrically opposite sides, clutch mechanism for independently connecting either of the main shaft gears to the shaft, manual means for operating such clutch mechanism, automatic means operated by the frame as it is carried to its final position for throwing out clutch mechanism, releasable means for supporting the hinge portion of the frame when the frame is carried to the turn position, and a sheaf receiver hingedly connected to the free end of the frame.

7. In a stoker, the combination with a stoker carriage and means for connecting the carriage to a binder, of a sheaf receiver turnably mounted upon the carriage, means for turning the receiver, means for carrying the sheaf receiver to an up-ended position upon the ground at the completion of its turning movement, means for delivering the sheaves from the binder into the receiver when in the normal position, supplemental means adapted to receive the sheaves from the discharging means during the up-ending of the shock, and means for up-setting such supplemental receiving means to discharge the sheaves contained therein into the main sheaf receiver.

8. In a stoker, the combination with a stoker carriage, means for connecting the carriage to a binder and a sheaf discharging device of a sheaf receiver turnably mounted upon the carriage, means for turning the receiver, means for carrying the sheaf receiver to an up-ended position upon the ground at the completion of its turning movement, means for delivering the sheaves from the binder into the receiver when in a normal position, a shaft mounted in bearings carried by the sheaf discharging device, a series of curved tines extending from the shaft and forming a supplemental sheaf receiver adapted to hang in the sheaf receiving position during the discharging of the shock, and means operated by the main sheaf receiver as it is brought to the receiving position for up-setting the supplemental receiver to discharge the sheaves therefrom into the main receiver.

9. In a stoker, the combination with a stoker carriage, means for connecting the carriage to a binder, and a sheaf discharging device of a sheaf receiver turnably mounted upon the carriage, means for turning the receiver, means for carrying the sheaf receiver in an upward position upon the ground at

- the completion of its turning movement, means for delivering the sheaves from the binder into the receiver when in a normal position, a shaft turnably mounted in bearings carried by the sheaf discharging device, a series of curved tines extending from the shaft to form a supplemental sheaf receiver, a crank arm at one end of the shaft, a bracket carried by the sheaf delivering means between the binder and the receiver, a lever mounted intermediately of its length upon such bracket, and against the free end of which the turnable mounting of the sheaf receiver is carried when the receiver is brought to the receiving position, and a link connecting one end of the lever with the crank arm of the shaft carried by a sheaf discharging device.
10. In a device of the class described, a stooker carriage, a frame divided into two portions hingedly connected together, means for turnably mounting one frame portion upon the carriage so as to leave the other frame portion free to move vertically, means for turning the frame, means for supporting the other portion of the frame during the turning movement, manually operated means for releasing the free portion of such frame when carried to the turned position, and a sheaf receiver connected to such released portion.
11. In a device of the class described, a stooker carriage, a frame divided into two portions hingedly connected together, means for turnably mounting one frame portion upon the carriage so as to leave the other frame portion free to move vertically, means for turning the frame, a roller journalled in the other frame portion, a curved track carried by the carriage over which the roller travels during the turning movement of the frame, means for releasably supporting the free portion of the frame as the roller passes off the track and the frame is brought to its final position, and a sheaf receiver connected to the free end of the frame.
12. In a device of the class described, a stooker carriage on one side of which sheaves are discharged, a frame divided into two portions hingedly connected together, means for turnably mounting one portion of the frame upon the carriage, means for turning the frame, a roller carried by the other portion of the frame, a curved track carried by the carriage and on which the roller travels during the turning movement of the frame, arms pivoted upon the discharge side of the carriage, a roller mounted between the arms and on to which the roller of the frame travels from the track, means for releasably supporting the arms, and a sheaf receiver connected to the other portion of the frame.
13. In a device of the class described, a stooker carriage, a frame divided into two portions, a receiver, a hinge rod connecting one frame portion and receiver together, means for turnably mounting one frame portion upon the carriage, a roller mounted in the other frame portion, a track mounted upon the carriage upon which the roller of the frame travels during the turning movement, tines extending upwardly from the hinged rod of the receiver to form a closure for one end thereof, a tension spring connecting the free end of the receiver with the frame, and means for releasably supporting the other portion of the frame when it is brought to the turned position.
14. In a stooker, a sheaf receiver supporting frame having a hinged portion, a sheaf receiver hingedly connected at one end to the free end of the hinged portion of the frame, and means for releasing the hinged portion to drop to the ground whereby the sheaf receiver is swung upward on its hinge to an up-ended position.
15. In a stooker, a sheaf receiver supporting frame having a hinged portion, a sheaf receiver hingedly connected at one end to the end of the hinged portion, and means for releasing the hinged portion to drop to the ground whereby the sheaf receiver is swung upward on its hinge to an up-ended position, and resilient means for returning the sheaf receiver into position against the hinge portion of the frame when relieved of the weight of the shock.

ISAAC NEWTON YOUNT.
